AIR RIFLE

Walter A. Tratsch, Chicago, Ill.

Application November 29, 1941, Serial No. 420,952

15 Claims. (Cl. 124—11)

This invention relates to improvements in air rifles and has as its principal object the provision of a trigger control for such rifle which will be simple in structure, economical in manufacture and highly efficient in use.

Another object of this invention is the provision of a trigger controlled air valve and a novel locking device for such trigger control after a predetermined number of shots have been projected from the rifle.

A further object of this invention is the provision of a valve control for air rifles which valve control will be uniform and positive in operation.

Other objects, advantages and novel aspects of this invention is found in the cooperative relationship of the various elements which contribute to the complete combination hereinafter described in view of the drawings in which:

Fig. 1 is a fragmentary side elevational view of a rifle stock embodying the invention;

Fig. 2 is a fragmentary perspective view of the rifle barrel and shot loading magazine associated therewith;

Fig. 3 is a fragmentary perspective view of an end of a breech block and is complementary to Fig. 2;

Fig. 4 is a bottom plan view, partly in section of the magazine as seen from line 4—4 in Fig. 1;

Fig. 5 is a vertical sectional detail through the rifle barrel and magazine as seen from line 5—5 in Fig. 1;

Fig. 6 is a bottom plan view of the breech block and trigger control embodying the present invention;

Fig. 7 is a perspective view of the breech block and trigger control associated therewith;

Fig. 8 is a side elevational view of the same as seen in Fig. 7 with parts in a different position;

Fig. 9 is a vertical sectional detail view taken through the breech block substantially along the long axis of the rifle barrel, looking in the direction of line 9—9 in Fig. 7;

Fig. 10 is an enlarged sectional detail view of a position of Fig. 9 illustrating a shot in position to be projected;

Fig. 11 is a sectional detail view of the shot elevator, similar to that of Fig. 9, but with parts in a different position; and

Fig. 12 is a vertical cross sectional detail view taken through the breech block substantially along line 12—12 in Fig. 9.

Referring to the drawings, the new air rifle is indicated at 10 and includes the customary stock 11, barrel 12 and breech housing 13. The stock

11 extends forwardly of the housing 13 to provide the usual hand grip 14 which is formed interiorly to provide a chamber 15 within which is disposed a loading magazine 16. This magazine 16 comprises a tubular member 17 slotted at the bottom as at 18 to provide a guideway for a pin 19 carried by a plunger 20 disposed to slide within the tube 17. The tube 17 has its fore end attached to the barrel 12 by means of a bracket 21 and its opposite end reduced to provide a shoulder 22 whereby the barrel 12 and tube 17 may be arranged parallel to each other by openings O formed in a breech block 23 later to be explained.

15 The plunger 20 is urged toward the breech block 23 by a spring 24 arranged behind the plunger 20 within the tube 17. In loading the rifle 10 a panel 25 is slid forwardly as seen in Fig. 2 to expose a loading port 26 to view. The panel 25 is guided for such sliding movement by a pair of guide blocks 27 extending therefrom and adapted to ride upon the barrel 12 along grooves 28 formed therein. A bolt 29 is provided on the panel 25 to facilitate a hand hold therewith to slide the panel 25 as aforesaid. A pin 30 is mounted upon the panel 25 for movement therewith and extends into the chamber 15 for engagement with the depending pin 19 carried by the plunger 20. The arrangement is such that movement of the panel 25 forwardly as before explained, causes movement of the plunger 20 against the action of the spring 24 to withdraw the plunger 20 from that region of the tube 17 to the left of the loading port 26 (Figs. 3 and 4).

35 The magazine is then loaded with shot in the form of balls 31 by pouring the latter, in predetermined and fixed numbers, into the port 26 for alignment within the magazine 16. The panel 25 is then returned to normal position (Fig. 1) wherein the spring-urged plunger will urge the balls toward the breech block 23 for successive use in a manner now to be described.

45 The present rifle is constructed to obtain air under pressure from an outside source. A nipple 32 extends downwardly from the breech block 23 and is adapted to be connected to any suitable conduit for conveying compressed air to the rifle. A passage 33 is formed in the breech block 23 to receive air from the nipple 32. A valve 34 is arranged at right angles to the passage 33 and comprises a plunger 35 having a cap 36 normally urged onto the valve seat by air pressure surging into the passage 33. The valve plunger 35 is reduced in its mid-section to permit air to pass

toward a jet 37 formed in the breech block 23 and communicating said valve 34 with the bore in the rifle barrel 12.

Disposed at the point of juncture of the jet 37 and the barrel 12 is the head end of a shot elevating device which comprises a tubular housing 38 vertically arranged with respect to the breech block 23 in a plane transversely of the parallelly disposed axis of the barrel 12 and loading magazine 16. An elevator block 39 is arranged in the housing 38 for vertical movement and is normally disposed in lowered position as seen in Fig. 9 with a shot receiving pocket 40 disposed in alignment with the tubular member 17 of the magazine 16. Extending from this pocket 40 is a passage 41 adapted to be aligned with the horizontal portion of the jet 37 and the bore of the barrel 12 as is seen in Fig. 10 when the block 39 is elevated in a manner now to be explained.

The housing 38 is slotted along one side as at 42 (Figs. 7 and 8) and arranged in this slot 42 is the free end 43 of a lever arm 44 pivotally mounted as at 45 upon the breech block 23. The end 43 of this lever 44 is in the form of a yoke and engages a cross pin 46 formed in a slotted bottom of the elevator block 39. The lever arm 44 has pin 47 and slot 48 connection with a trigger member 49 pivotally arranged as at 50 upon the breech block 23. The slot 48 is formed in the lever 44 while the pin 47 is carried by the trigger member 49. The arrangement is such that when the trigger 49 is pulled back in normal shooting fashion the pin 47 rides in the curved slot 48 to cam the lever 44 into the position shown in Fig. 8. The yoke end 43 of the lever 44 thus raises the elevator block 39 from the position shown in Fig. 9 to that shown in Fig. 10, with the elevated ball 31 abutting a rubber washer 51 having a restricted aperture 52 to hold the ball 31 in the pocket 40 until a charge of compressed air is emitted into the jet 37 upon the opening of the valve 34.

The valve opening operation commences simultaneously with the foregoing ball elevating operation so that a charge of compressed air is emitted substantially upon the arrival of the ball into alignment with the bore of the barrel 12. An electromagnetic solenoid 53 is arranged on the breech block 23 with the axis of movement of its armature 54 in axial alignment with the valve plunger 35, a portion of which extends partially into the guide sleeve 55 of the solenoid 53. The armature 54 is urged by a spring 56 into extreme withdrawn condition (Fig. 9) with its free end engaging a stop 57 attached to the breech block by means of a screw 58.

The solenoid 53 includes a coil 59 which is adapted to be energized momentarily, once, upon each operation of the trigger member 49. A novel control means is provided for synchronizing the action of the trigger with the elevation of balls to firing position. This control means includes a set of electrical switches operable by the trigger member together with time delay means for effecting a positive and uniform operation of the valve 34 upon each pull of the trigger. A time switch 60 is best seen in Figs. 7 and 8 as having a stationary contact 61 and a movable contact 62 adapted normally to be in broken circuit condition as seen in Fig. 7. This movable contact 62 is carried by an oscillating member 63 pivoted as at 64 on the breech block 23 and having its lower end normally urged, by spring means 65 attached thereto, toward the trigger member 49, the latter being likewise urged

toward the oscillating member 63 by the same spring means 65. The lever arm 44, heretofore described, is likewise urged into normal condition by a spring 66 which is anchored to the lower end of the oscillating member 63 as seen in Fig. 7.

The trigger member 49 has a laterally extending arm 67 adapted to rotate about the pivot mounting 50 when the trigger is actuated. The end of this arm 67 scribes an arc adjacent the oscillating member 63 and engages a trip finger 68 pivotally arranged as at 69 upon the oscillating member 63 in a manner such as to effect a rotation of the latter about its pivotal mounting 64 counterclockwise (see Fig. 3). When the end of arm 67 passes the trip finger 68, the member 63 will be urged back toward normal position by the spring means 65 with the movable contact 62 sweeping over the stationary contact 61. This return movement of the oscillating member is retarded by means of a dash pot 69', the piston rod 70 of which has pin 71 and slot 72 connection with the oscillating member 63, the latter carrying the pin 71.

This delayed return movement of the oscillating member 63 assures that contact will be made through a trigger switch 73 attached to the under side of the breech block 23 adjacent the trigger member 49. An insulated pin 74 extends laterally from the trigger member 49 and is adapted to operatively engage the leaf spring switch 73 to position the latter in circuit completing condition during the last fraction of movement of the trigger member 49.

An electrical circuit is provided by a conductor element 75 entering the stock of the gun with a positive conductor connected to one side of the trigger switch 73, the opposite side of which is connected to the movable contact 62. The stationary contact 61 connects circuit from the time delay switch 60 to one side of the coil 59, the opposite side of which connects to the negative conductor of the element 75.

By the foregoing operation of the trigger 49, the electrical circuit is then completed to the coil 59 to energize the latter, thus causing the armature 54 to plunge in hammer-like action against the extending end portion of the valve plunger 35. By this movement of the plunger 35, the cap 36 is displaced from its valve seat, thereby allowing a charge of compressed air to enter the jet 37 with a blast that surges through the passage 41 to force the already elevated ball 31 out of the pocket 40 through the bore of the rifle barrel 12 along a predetermined trajectory governed by the aim of the rifle.

After a time lapse sufficient to give the charge necessary to blast the ball clear out of the bore of the barrel 12, the spring means 65 will have urged the oscillating member 63 back to normal condition against the action of the dash pot 69. The coil 59 of the solenoid 53 will therefore become deenergized immediately after the predetermined charge of air has been effected and the trigger member 49 may now be released to permit the mechanism to again assume a normal condition.

In returning to normal condition, the short elevating block 39 is lowered into a position with the pocket 40 in alignment with the tube 17 of the loading magazine 16, whereupon the next ball 31 will be urged into a position for elevation as heretofore described. However, should the last ball 31 have been projected from the barrel 12 in the manner hereinbefore explained, the plunger 20 of the shot loading magazine 16 will be bearing

against the elevating block 39 so that when the latter returns to lowered or normal position the free end of the plunger 20 will seat in the pocket 40 (Fig. 11). This is among the salient objects of my invention, in that it provides a locking means for the shot elevator determined upon the projection of the last shot in the magazine 16. By reason of the interrelationship of the trigger member 49 with the elevation of the balls 31, the trigger member 49 likewise becomes locked against further action after the last shot has been accomplished. By the same token there can be no use of electrical current after the gun is locked, thus conserving electrical energy and for the same reason air pressure is not releasable and therefore likewise it is not wasted.

It is therefore seen that I have provided a novel air rifle which is adapted for use in ranges requiring uniform air charges necessary to maintaining accuracy in aim; and that I have provided a trigger mechanism of simple structure which is self-locking upon completion of a predetermined number of shots, which is highly advantageous in arcade gallery equipment, or any other range-practicing equipment in use.

While I have illustrated and described the preferred form of construction for carrying my invention into effect, this is capable of variation and modification without departing from the spirit of the invention. I therefore do not wish to be limited to the precise details of construction set forth, but desire to avail myself of such variations and modifications as come within the scope of the appended claims.

Having thus described my invention, what I claim as new and desire to protect by Letters Patent is:

1. In an air rifle having a supply source of compressed air to a breech block, a barrel, a magazine arranged beneath said barrel and adapted to contain aligned balls, ball elevating means communicating with said barrel and said magazine and having a ball seat formed therein normally disposed to receive balls from the magazine, means urging said balls toward said ball elevating means and adapted, when no ball is disposed in said rifle, to enter said ball seat and prevent movement of said ball elevating means, a lever pivotally arranged on said breech block and having its free end operatively engaging said ball elevating means, a trigger member operatively connected to said lever to cam the latter for raising said ball elevating means into alignment with said barrel, and manually operable bolt means slidably arranged on said barrel and having operative engagement with said means for urging balls toward said elevating means to withdraw the same from said ball seat to permit reloading of balls into said magazine.

2. In an air rifle having a supply source of compressed air to a breech block, a barrel, a magazine arranged beneath said barrel and adapted to contain aligned balls, ball elevating means communicating with said barrel and said magazine and normally disposed to receive balls from the latter, ball urging means urging said balls toward said ball elevating means and adapted, when the last ball has been elevated, to engage and lock said ball elevating means, a lever pivotally arranged on said breech block and having its free end operatively engaging said ball elevating means, a trigger member operatively connected to said lever to cam the latter for raising said ball elevating means into align-

ment with said barrel, valve means in said breech block between said supply source and said barrel, and means operatively associated with said trigger member for affecting said valve means to emit a charge of compressed air into said barrel, and means for facilitating a reloading of balls into said magazine, said means including a sliding bolt arranged for movement along said barrel and adapted to engage said ball urging means to withdraw the latter in a direction away from said ball elevating means.

3. In an air rifle having a supply source of compressed air to a breech block, a barrel, a magazine arranged beneath said barrel and adapted to contain aligned balls, means urging said balls toward said breech block, ball elevating means communicating with said barrel and said magazine and normally disposed to receive balls from the latter, a lever pivotally arranged on said breech block and having its free end operatively engaging said ball elevating means, a trigger member operatively connected to said lever to cam the latter for raising said ball elevating means into alignment with said barrel, valve means arranged in said breech block intermediate said barrel and said supply source and normally disposed in closed condition by the latter, a solenoid having an armature in axial alignment with said valve means for opening the latter upon energization of said solenoid, normally opened switch means arranged in an electrical circuit with said solenoid, said switch means including a stationary contact and an oscillating contact member, and spring means normally urging the latter out of engagement with said stationary contact, said trigger mechanism operatively engaging said oscillating contact member to urge the latter into wiping electrical contact with said stationary contact to energize the solenoid for the purpose aforesaid.

4. In an air rifle having a supply source of compressed air to a breech block, a barrel, a magazine arranged beneath said barrel and adapted to contain aligned balls, means urging said balls toward said breech block, ball elevating means communicating with said barrel and said magazine and normally disposed to receive balls from the latter, a lever pivotally arranged on said breech block and having its free end operatively engaging said ball elevating means, a trigger member operatively connected to said lever to cam the latter for raising said ball elevating means into alignment with said barrel, valve means arranged in said breech block intermediate said barrel and said supply source and normally disposed in closed condition by the latter, a solenoid having an armature in axial alignment with said valve means for opening the latter upon energization of said solenoid, normally opened switch means arranged in an electrical circuit with said solenoid, means on said trigger member and engageable with said switch means to close the latter to energize the solenoid for the purpose aforesaid, and time delay means for said electrical circuit for breaking said circuit after a predetermined length of time.

5. In an air rifle having a supply source of compressed air to a breech block, a barrel, a magazine arranged beneath said barrel and adapted to contain aligned balls, means urging said balls toward said breech block, ball elevating means communicating with said barrel and said magazine and normally disposed to receive balls from the latter, a lever pivotally arranged on said breech block and having its free end op-

eratively engaging said ball elevating means, a trigger member operatively connected to said lever to cam the latter for raising said ball elevating means into alignment with said barrel, valve means arranged in said breech block intermediate said barrel and said supply source and normally disposed in closed condition by the latter, a solenoid having an armature in axial alignment with said valve means for opening the latter upon energization of said solenoid, normally opened switch means arranged in an electrical circuit with said solenoid, means on said trigger member and engageable with said switch means to close the latter to energize the solenoid for the purpose aforesaid, time delay means for said electrical circuit for breaking said circuit after a predetermined length of time, said last named means including an oscillating member, spring means urging the latter into a normal position, said trigger mechanism operatively engaging the oscillating member for operation against the action of said spring, a stationary contact element, a contact element carried by and movable with said oscillating member for movement into circuit completing condition with said stationary contact, and a dash pot operatively connected to said oscillating member to retard movement of the latter by said spring means.

6. In an air rifle having a supply source of compressed air to a breech block, a barrel, a magazine arranged beneath said barrel and adapted to contain aligned balls, means urging said balls toward said breech block, ball elevating means communicating with said barrel and said magazine and normally disposed to receive balls from the latter, a lever pivotally arranged on said breech block and having its free end operatively engaging said ball elevating means, and a trigger member operatively connected to said lever to cam the latter for raising said ball elevating means into alignment with said barrel, said means for urging said balls toward said breech block adapted to engage said ball elevating means to lock the latter against movement of the trigger aforesaid after all the balls have been elevated.

7. In an air rifle having a supply source of compressed air to a breech block, a barrel, a magazine arranged beneath said barrel and adapted to contain aligned balls, means urging said balls toward said breech block, ball elevating means communicating with said barrel and said magazine and normally disposed to receive balls from the latter, a lever pivotally arranged on said breech block and having its free end operatively engaging said ball elevating means, a trigger member operatively connected to said lever to cam the latter for raising said ball elevating means into alignment with said barrel, said means for urging said balls toward said breech block adapted to engage said ball elevating means to lock the latter against movement of the trigger aforesaid after all the balls have been elevated, valve means in said breech block between said supply source and said barrel, and means operatively associated with said trigger member for affecting said valve means to emit a charge of compressed air into said barrel.

8. In an air rifle having a supply source of compressed air to a breech block, a barrel, a magazine arranged beneath said barrel and adapted to contain aligned balls, means urging said balls toward said breech block, ball elevating means communicating with said barrel and

said magazine and normally disposed to receive balls from the latter, a lever pivotally arranged on said breech block and having its free end operatively engaging said ball elevating means, a trigger member operatively connected to said lever to cam the latter for raising said ball elevating means into alignment with said barrel, said means for urging said balls toward said breech block adapted to engage said ball elevating means to lock the latter against movement of the trigger aforesaid after all the balls have been elevated, valve means arranged in said breech block intermediate said barrel and said supply source and normally disposed in closed condition by the latter, a solenoid having an armature in axial alignment with said valve means for opening the latter upon energization of said solenoid, normally opened switch means arranged in an electrical circuit with said solenoid, and means on said trigger member and engageable with said switch means to close the latter to energize the solenoid for the purpose aforesaid.

9. In an air rifle having a supply source of compressed air to a breech block, a barrel, a magazine arranged beneath said barrel and adapted to contain aligned balls, means urging said balls toward said breech block, ball elevating means communicating with said barrel and said magazine and normally disposed to receive balls from the latter, a lever pivotally arranged on said breech block and having its free end operatively engaging said ball elevating means, a trigger member operatively connected to said lever to cam the latter for raising said ball elevating means into alignment with said barrel, said means for urging said balls toward said breech block adapted to engage said ball elevating means to lock the latter against movement of the trigger aforesaid after all the balls have been elevated, valve means arranged in said breech block intermediate said barrel and said supply source and normally disposed in closed condition by the latter, a solenoid having an armature in axial alignment with said valve means for opening the latter upon energization of said solenoid, normally opened switch means arranged in an electrical circuit with said solenoid, means on said trigger member and engageable with said switch means to close the latter to energize the solenoid for the purpose aforesaid.

10. In an air rifle having a supply source of compressed air to a breech block, a barrel, a magazine arranged beneath said barrel and adapted to contain aligned balls, means urging said balls toward said breech block, ball elevating means communicating with said barrel and said magazine and normally disposed to receive balls from the latter, a lever pivotally arranged on said breech block and having its free end operatively engaging said ball elevating means, a trigger member operatively connected to said lever to cam the latter for raising said ball elevating means into alignment with said barrel, said means for urging said balls toward said breech block adapted to engage said ball elevating means to lock the latter against movement of the trigger aforesaid after all the balls have been elevated, valve means arranged in said breech block intermediate said barrel and said supply source and normally disposed in closed condition by the latter, a solenoid having an

armature in axial alignment with said valve means for opening the latter upon energization of said solenoid, normally opened switch means arranged in an electrical circuit with said solenoid, means on said trigger member and engageable with said switch means to close the latter to energize the solenoid for the purpose aforesaid, time delay means for said electrical circuit for breaking said circuit after a predetermined length of time, said last named means including an oscillating member, spring means urging the latter into a normal position, said trigger mechanism operatively engaging the oscillating member for operation against the action of said spring, a stationary contact element, a contact element carried by and movable with said oscillating member for movement into circuit completing condition with said stationary contact, and a dash pot operatively connected to said oscillating member to retard movement of the latter by said spring means.

11. In a rifle of the class described including a breech block, a barrel, a shot magazine, a plunger in said shot magazine, means communicating said magazine with said barrel, said means comprising a shot elevating device having a shot seat formation normally aligned with said shot magazine, spring means normally urging said plunger toward said shot seat and adapted to urge the plunger into said seat when no shot is disposed therebetween, means for reciprocating said shot elevating device from normal alignment with said shot magazine to alignment with said barrel when shot is disposed in said shot seat, and trigger mechanism for said rifle operatively associated with said last named means for effecting movement of the latter as aforesaid when the trigger mechanism is operated to effect projection of a shot from said barrel.

12. In a rifle of the class described including a breech block, a barrel, a shot magazine, a shot conveyor disposed in said breech block between said barrel and shot magazine for conveying shot from the magazine to the barrel, trigger mechanism for said rifle, means operatively associated with said trigger mechanism and said shot conveyor for affecting movement of the latter for the purpose aforesaid, and trigger locking means in said magazine adapted to engage and lock said shot conveyor after the last shot has been projected from said rifle.

13. In a rifle of the class described including a breech block, a barrel, a shot magazine, means communicating said magazine with said barrel, said means comprising a shot elevating device, means for reciprocating said shot elevating device from normal alignment with said shot magazine to alignment with said barrel, means in said shot magazine for urging shot toward said elevating device and including means adapted to extend transversely of the direction of move-

- ment of said shot elevating device when no shot is disposed in said rifle to prevent reciprocation of said elevating means, trigger mechanism for said rifle operatively associated with said shot elevating means for joint movement with the latter when the trigger mechanism is operated to effect projection of a shot from said barrel, and valve means arranged in said breech block, means for displacing said valve to permit a charge of air to be emitted through said barrel, said last named means being affected for operation only when said trigger mechanism and said shot elevating device are free for joint movement as aforesaid.
14. In a rifle of the class described including a breech block, a barrel, a shot magazine, means communicating said magazine with said barrel, said means comprising a shot elevating device, means for reciprocating said shot elevating device from normal alignment with said shot magazine to alignment with said barrel, trigger mechanism for said rifle operatively associated with said last named means for effecting movement of the latter as aforesaid when the trigger mechanism is operated to effect projection of a shot from said barrel, and valve means arranged in said breech block, means for displacing said valve to permit a charge of air to be emitted through said barrel, said last named means being affected for operation by said trigger mechanism, and trigger locking means in said magazine adapted to engage and lock said elevating device against further operation after the last shot has been projected from said barrel.
15. In a rifle of the class described including a breech block, a barrel, a shot magazine, means communicating said magazine with said barrel, said means comprising a shot elevating device, means for reciprocating said shot elevating device from normal alignment with said shot magazine to alignment with said barrel, trigger mechanism for said rifle operatively associated with said last named means for effecting movement of the latter as aforesaid when the trigger mechanism is operated to effect projection of a shot from said barrel, valve means arranged in said breech block, means for displacing said valve to permit a charge of air to be emitted through said barrel, said last named means being affected for operation by said trigger mechanism, and means for locking said trigger mechanism against further operation after the last shot has been projected from said barrel, said locking means including a spring-urged plunger arranged to reciprocate in said shot magazine to urge said shot toward said shot elevating device and to engage said last named device to restrain its normal movement by the trigger mechanism as aforesaid.
